UNITED STATES PATENT OFFICE

EDWARD H. STEARNS, OF ERIE, PENNSYLVANIA.

IMPROVEMENT IN LOG-TURNERS FOR SAW-MILLS.

Specification forming part of Letters Patent No. 147,523, dated February 17, 1874; application filed March 21, 1873.

To all whom it may concern:

Be it known that I, EDWARD H. STEARNS, of Erie, in the county of Erie and State of Pennsylvania, have invented a new and useful Improvement in Log-Turners for Saw-Mills; and I do hereby declare the following to be a full, clear, and exact description thereof, reference being had to the accompanying drawing making a part of this specification, in which—

Figure 1 is a sectional view of my machine in a vertical plane just at one side of the vertically-moving bar which turns the log. Fig. 2 is a detached outline elevation of the chains and their connections, and illustrative of their operation in connection with the bar. Fig. 3 is a rear-edge elevation of the bar, with its pulleys, but with only the outside chain-connections. Fig. 4 is a detached view of a portion of the toothed chain. Fig. 5 is a like view of one of the hinged teeth.

Like letters of reference indicate like parts in each.

My invention relates to improvements in the construction of log-turners for saw-mill use.

To enable others skilled in the art to make and use my invention, I will proceed to describe its construction and mode of operation.

The saw-carriage is represented at A, the knees at A', and the log to be turned at B. The frame D is of any suitable construction. The vertically-moving bar G is made of two side or cheek plates, d d, Fig. 3, held at the desired distance apart by distance-pieces or washers, or in other known way. It has a pulley, a, at its upper end; a like pulley, a¹, at its lower end; and a pulley, a², at any desired point between its ends, but preferably near its lower end, such pulley a² being, by its shaft or pin, connected with a swinging arm, b, pivoted or hinged at b¹. A pulley, f, is arranged on the upper part of the frame D. A windlass-shaft, f¹, and wheel f² receive motion from a band-wheel, g, and friction-wheel g¹, the latter bearing, when desired, on the wheel f². The shaft of the wheels g g¹ is mounted in a rocking-frame, so as to be shifted in and out of gear with the wheel f² at pleasure, which is done by means of a lever, g², or in any other manner known in the art for accomplishing the same result. An ordinary chain-connection, s, extends from the windlass f¹ over the

pulley f, under the pulley a², and over the pulley a from the outside; but before coming to the side of the pulley next the log B, it connects with a chain, S, made of suitably-formed links, as shown in Fig. 4, which chain extends as far as may be desired in connection with its action on the log B. It then passes under the pulley a¹, and connects with another ordinary chain, s¹, which branches—one branch extending up, and being secured to the beams D² of the frame-work; one on each side of the turning-bar G, as illustrated in Fig. 3. The toothed chain S, while in operation, rests against a diaphragm, i, which extends up and down between the plates d d, which make up the bar G, at such distance from their edge as to constitute therewith mechanically a groove, in which the chain slides up and down, but with its teeth projecting so as to engage the log. To the chain S, substantially in the manner indicated in Fig. 4, I attach a series of hook-shaped teeth, e e¹ e². These teeth are pivoted or hinged loosely to the chain-links, either between two link-bars, as shown, or the base end may be bifurcated and pivoted to the single bars. In either case the tooth is so attached that, when thrown out and moving upward, it will, by coming against the end of the next link, or by means of other suitable stop device, be held in the position shown at e. Its point will then engage the log, as illustrated in Fig. 1. At the same time the teeth are so attached to the chain that, with a downward motion of the bar G, they may fold in, as at e¹, Fig. 5, and thereby be free to slide down on the side of the log without engaging it so as to revolve it back; and as the chain-links pass over the upper pulley the teeth fold forward, as described, and as shown at e², so that their points will not be liable to interfere with the operation of the machine by hooking onto any of the other parts of the apparatus.

It will now be seen that, by winding up the chain s on the windlass-shaft or drum f¹, the toothed chain S will be caused to move upward, and, by its teeth e, engage the log B and turn it over. Also, as the chain-connection is fixed at its opposite end to a stationary part, D², of the frame-work, and passes under the pulleys a¹ a², the entire frame or bar G will be caused to move upward against the side of the

log, carrying the toothed chain S with it, and so turning the log. After the log is turned the chain is slackened, and the bar G comes down to its former position, which is represented by dotted lines in Fig. 1.

In order that the upper end of the bar G shall always, when being elevated in the manner described, swing forward, so as to bring the teeth e against the side of the log, I arrange the pulleys in such way that, in winding up the chain, the lower end of the frame or bar G will be drawn back of a vertical line passing through its center of gravity. The upper end will then necessarily fall over against the log, and the direction in which the forces act is such that the bar G will be held over in that position.

The function of the bar G —hugging the log while moving upwardly—is thus automatically secured; but, if so preferred, suitable guides, or other known equivalent means, may be employed for the same purpose. The lower end of the bar G is prevented from swinging back away from the log by means of the arm b .

In order, now, that, after the log is turned and the bar D has come down to its former position, the upper end of the bar may swing back clear of the saw-carriage, I hang the bar by chains s^2 , which, at one end, are fastened to some fixed part, D^3 , of the frame-work, and at the other end to the bar G by projecting arms d' , at points which shall be forward of a vertical line passing through the center of gravity of the bar G .

In connection with the chain as a carrier for the teeth, a rigid tooth may be employed, or one that is rigid in reference to the link with which it is connected, though the construction above described is preferable.

Mechanically, the bar G and the toothed

chain S together constitute the lifting or turning bar; and any suitable device which will hold the toothed chain up to the log at the point of bite may be substituted for the bar G .

I do not claim, broadly, the application, as a log-turner, of the ordinary hoisting endless chain, with hooks attached, and passing over pulley-wheels, which latter are mounted in fixed stationary bearings, though I am not aware that such device has ever been so used, or that its use has ever before been suggested.

What I claim as my invention, and desire to secure by Letters Patent, is—

1. In a log-turner, a toothed chain, S , which is movable, at the pleasure of the workman, up and down as well as to and from the log, in combination with a back rest for holding the teeth up to the log at the point of bite, constructed substantially in the manner set forth.

2. The combination of toothed chain S , vertically-moving bar G , such chain having a connection at one end to a coiling-shaft and at the other end to the frame, and a system of pulleys whereby both chain and bar shall move vertically at the same time, substantially as set forth.

3. The chains s^2 , in combination with the projecting arm d' of the bar G , substantially as set forth.

4. The combination of a toothed chain, S , vertically-moving bar G , and arm b , arranged substantially as and for the purposes set forth.

In testimony whereof I, the said EDWARD H. STEARNS, have hereunto set my hand.

EDWARD H. STEARNS.
